Primary Examiner — Holly E Thurman*Assistant Examiner* — Altaira J Swangin*(74) Attorney, Agent, or Firm* — Georgi Korobanov(57) CLAIM

The ornamental design for a mini personal computer, as shown and described.

DESCRIPTION

FIG. 1 is a perspective view of a mini personal computer, showing my new design;
FIG. 2 is another perspective view thereof;
FIG. 3 is a front view thereof;
FIG. 4 is a rear view thereof;
FIG. 5 is a left side view thereof;
FIG. 6 is a right side view thereof;
FIG. 7 is a top plan view thereof;
FIG. 8 is a bottom plan view thereof; and,
FIG. 9 is an enlarged view of portion 9 shown in FIG. 1. The even-dash broken lines shown in the drawings illustrate portions of the mini personal computer that form no part of the claimed design. The dash-dot broken lines represent the extent of the detail views and form no part thereof.

1 Claim, 9 Drawing Sheets(56)
